UNITED STATES PATENT OFFICE.

DANIEL C. MONAHAN, OF WARREN, ILLINOIS.

TRACK CONSTRUCTION.

Application filed October 29, 1921. Serial No. 511,266.

To all whom it may concern:

Be it known that I, DANIEL C. MONAHAN, a citizen of the United States, and a resident of Warren, in the county of Jo Daviess, in the State of Illinois, have invented a new and useful Improvement in Track Constructions, of which the following is a full, clear, and exact description.

My invention relates to improvements in track construction, and it consists in the combinations, constructions and arrangements herein described and claimed.

An object of my invention is to provide splice-plates for securing rails together without the use of separate bolts and nuts.

Another object of my invention is to provide a means of securing rails together having relatively few parts, all of which parts are interchangeable.

20 A further object of my invention is to provide splice-plates of the nature described, adapted to engage the rails in standard holes as provided in the web of the rails.

25 Other objects and advantages will appear in the following specification, and the novel features of the invention will be particularly pointed out in the appended claims.

30 My invention is illustrated in the accompanying drawings forming part of this application, in which

Figure 1 is a perspective view of the splice-plates operatively applied,

35 Figure 2 is a sectional view on the line 2-2 of Figure 1, and

Figure 3 is a sectional view on the line 3-3 of Figure 2.

In carrying out my invention, I make use 40 of track rails 1 and 2, having holes of a standard specification 3 and 4, drilled in webs 5 and 6. The rails 1 and 2 are placed so that their ends 7 and 8 abut.

Splice-plates 9 having two projections 45 thereon, are placed one on each side of the webs 5 and 6 of the rails 1 and 2, so that the projections of each plate 10 pass through two of the holes 3 and 4, one in rail 1, the other in rail 2. Holes 11 in 50 the splice-plates 9, provide means for the projections 10 to pass on through the splice-plates and extend beyond the surface thereof.

The projections 10 and the holes 11 are 55 so arranged that the splice-plates 9 are

alike in construction and are interchangeable as is clearly shown in Figure 2.

Means for rigidly holding the rails 1 and 2 between the splice-plates 9 is provided by metal wedges 12, disposed in slots 60 13 in the projections 10 and bearing against the outer surface of the splice-plates and the outer side of the slots 13.

The inner surfaces of the splice-plates 9 are made to conform with the shape of the 65 web 6 and the base 14 of the rails and fit closely thereto when the wedges 12 are tightened in their respective slots 13.

From the foregoing description of the 70 various parts of the device, the operation thereof may be readily understood. The rails 1 and 2 are laid in the positions desired, their ends 7 and 8 abutting. One of the two splice-plates 9 is then placed against the two rails so that one of the two 75 projections 10 passes through one of the holes in rail 1, and the other through one of the holes in rail 2. This must be done so that the remaining two holes in rails 1 and 2 are in line with the two holes 11 in the 80 splice-plate. The other splice-plate is then placed against the rail so that its projections 10 pass through the two remaining holes therein and through the first splice-plate. The wedges 12 are then hammered into the 85 slots 13 in the projections 10 and the work of securing the rails 1 and 2 together is completed.

Means for preventing the wedges 12 from 90 working out of the projections 10 is provided by cotter pins 15 which are disposed in one of a plurality of holes 16 through the lower end of the wedges 12. This is clearly shown in Figure 3.

I claim:

1. The combination with abutting rail ends having bolt openings provided therein, of a splice plate disposed on each side of said rail ends, and arranged to overlap the abutting ends, each of said splice plates having integral projections, alternately arranged in alignment with one another, and arranged to register with said bolt openings in said rail ends respectively, and the projections of each splice plate extending 105 through the rail ends, and through the openings in the other splice plate, said projections having tapering openings, adjacent the ends thereof, and metal wedges adapted to enter the tapered openings, and bear 110

against the outer surface of said splice plate and said projection for drawing said splice plate into close engagement with said rail ends when said wedges are hammered 5 down.

2. The combination with abutting rail ends having bolt openings provided therein, of a splice plate disposed on each side of said rail ends, and arranged to overlap 10 the abutting ends, each of said splice plates having integral projections alternately arranged in alignment with one another, and arranged to register with said bolt openings in said rail ends respectively, and the

projections of each splice plate extending 15 through the rail ends, and through the openings in the other splice plate, said projections having tapering openings, adjacent the ends thereof, and metal wedges adapted to enter the tapered openings, and bear 20 against the outer surface of said splice plate and said projection for drawing said splice plate into close engagement with said rail ends when said wedges are hammered down, said splice plates being exactly alike in construction and interchangeable. 25

DANIEL C. MONAHAN.
